DEVICE FOR MEDICATING SMOKE

James L. Jordan, Jr., and Tyson A. Curtis,
Hartsville, S. C.

Application September 6, 1933, Serial No. 633,376

4 Claims. (Cl. 131—10)

This invention relates to a device for medicating smoke, the general object of the invention being to provide a cigarette holder, cigar holder or pipe stem, so constructed as to provide a convenient, effective and efficient way of taking substances of various kinds into the body with the smoke for the purpose of effecting relief from various diseases, ailments, irritations, etc., controlling bad breath and for giving a better taste to the smoke and mouth.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation of the invention, showing the same in use as a cigar or cigarette holder.

Figure 2 is a longitudinal sectional view.

Figure 3 is a fragmentary top plan view.

Figure 4 is a view of the cartridge.

Figure 5 is a section on line 5—5 of Figure 2.

Figure 6 is a section on line 6—6 of Figure 2.

Figure 7 is a section on line 7—7 of Figure 2, showing the intake valves open.

Figure 8 is a similar view, showing said valves closed.

Figure 9 is a section on line 9—9 of Figure 2.

As before stated, the invention can be used with a cigarette holder, a cigar holder or a pipe, but in order to simplify the description, the device will be referred to as a cigarette holder.

In these drawings, the numeral 1 indicates the mouth piece and the numeral 2 indicates a tube having its bore forming a continuation of the bore of the mouth piece and said tube extends well beyond the inner end of the mouth piece. The numeral 3 indicates a cylinder, the major portion of which forms a chamber 4 through which the tube 2 passes. The inner end of the mouth piece is reduced, as shown at 5, and the adjacent end of the cylinder 3 telescopes this reduced end and the parts are held together by friction, but said parts can be rotated relative to each other.

The front end of the cylinder is formed with a socket 6 to receive a cigarette or a cigar or, as before stated, the device can be used with a pipe. At the inner end of the socket is a reduced short bore 7 which receives the front end of the tube 2 and between the front end of the chamber 4

and this bore 7 are located the radial recesses 8 preferably shaped as shown in Figure 2 and preferably arranged as shown in Figure 6, these recesses opening out into the front end of the chamber 4. The front end of the tube 2 is formed with the outwardly and forwardly sloping ports 9 which, when the parts are in one position, will communicate with the recesses 8, but when the parts are in another position, said ports will be closed by the solid portions of the cylinder 3 located between the recesses 8. Thus these ports 9 act as out-take valves for controlling communication between the front end of the tube 2 and the front end of the chamber 4.

Recesses 10 are formed in the reduced end 5 of the mouth piece and outwardly and rearwardly sloping ports 11 are formed in the rear end of the cylinder 3 and when the members 1 and 3 are in a certain position, the ports 11 will communicate with the recesses 10, as shown in Figure 7, but when the parts 1 and 3 are partly rotated relative to each other, the ports 11 will be out of communication with the recesses 10, as shown in Figure 8. These ports 11 and recesses 10 act as intake valves for controlling the admission of air to the rear end of the chamber 4.

The mouth piece 1 is provided with a groove 12 (see Figure 3), into which extends a projection 13 on the cylinder 3, this groove and projection limiting relative rotary movement between the parts 1 and 3, and indicia, shown generally at 14, is placed on the mouth piece adjacent the groove 12 and the projection 13 acts as a marker for said indicia so as to indicate the condition of the valve means. As shown in Figure 3, when the projection 13 is in the central position and opposite the letter C, both sets of valves are closed. When the cylinder has been partly rotated to the left to place the projection 13 opposite the numeral 1, the ports 9 will be in communication with the recesses 8 and when the projection 13 is opposite the numeral 2, both sets of valves will be opened so that air can enter the rear end of the cylinder 4 and the front end of the tube 2 will be in communication with the front end of the chamber.

A container A is adapted to be placed in the chamber 4 and this container is preferably formed of a perforated cylinder 15 having its ends closed by perforated disks 16, one of which is frictionally held in the cylinder and a tube 17, also perforated, passes through the central part of the cylinder and surrounds the smoke tube 2 and has its ends passing through the disks 16. This cylinder A is to contain suitable substances, as will be

hereinafter described, and it has tongues 18 projecting from its ends for engaging the end walls of the chamber 4 so that the ends of the container A, composed of the disks 16, are spaced from the ends of the chamber 4. The cylinder 15 is of slightly less diameter than the diameter of the chamber 4, as shown in Figure 2, so as to leave a slight space around the cylinder.

Thus it will be seen that if both sets of valve means are opened, air will enter the rear end of the chamber 4 and mix with the vapors of the substances in the container A and then pass through the recesses 8 and ports 9 into the smoke pipe 2, where the mixture of air and vapors will mix with the smoke and thus pass into the mouth of the user. By closing the rear set of valves, the vapors from the substances will pass into the smoke tube without being mixed with air and by closing both sets of valves, only the smoke will pass into the mouth of the user. Of course, by but partly closing the valve means, the amount of vapors either mixed with air or not mixed with air, passing into the smoke tube, can be regulated.

It is our idea to have a series of such cartridges composed of volatile substances that are beneficial in the prevention and treatment of various diseases, ailments and irritations, such as colds, asthma, halitosis, etc. Also, in this series there will be cartridges that will render a more pleasant taste to the smoke, that will render a more pleasant taste to the mouth, and that will render a more pleasant odor to the breath. Some of these cartridges will be composed of substances that will serve a double or multiple purpose. An illustration of this type of cartridge is one that is composed of menthol, camphor, ammonium carbonate and aromatic substances in the proper proportions. Obviously, while this cartridge is beneficial in the treatment of colds, it also would render a more pleasant taste to the smoke and mouth.

There can be no hard and fast rules regarding the method of construction of the cartridges because of the different properties possessed by the various ingredients composing them. In the case of slightly volatile substances, we will make the cartridges more porous by perforating them with holes or in some other effective way.

In some of the cartridges that are composed of solid substances, we will mould or crystallize them into form, while in others we will bind them into form with a suitable fibrous material or encase them in a perforated or porous shell. In some cases of liquid substances, we will employ suitable solids having the desired form to absorb the liquid, while in other cases, we will use absorbents, such as cotton encased in a perforated shell having the desired size and shape, to absorb the liquid.

In addition to the series described above, we will have blank cartridges to be filled at drug stores according to the user's physician's prescription. Those for solid substances will be constructed of suitable materials having the form of porous or perforated shells. The ones for liquids will be made of absorbents having the desired form and size or they will be made of absorbents encased in porous or perforated shells.

For substances that range from slightly to medium volatile, the user rotates the parts until the indicator shows that all of the valves are open or partly open, depending upon the degree of volatility and the notion of the individual user. In this case, air will enter through the intake

valves, mix with the volatized substances, and pass through the out-take valves into the smoke passage tube. This mixture, together with the smoke, passes into the mouth.

For substances that range from medium to extreme volatility, the parts are rotated until the indicator shows that the intake valves are closed, while the out-take valves are open or partly open, depending upon the degree of volatility and the notion of the individual user. In this case, the volatized substance will pass through the out-take valves into the smoke passage tube and together with the smoke will be conducted into the mouth.

In case the user wanted to use the device as an ordinary cigarette holder, he could do so by rotating the parts until the indicator showed that all valves were closed.

This device can also be used by people who do not smoke, that is, it can be used for purely its medical value by simply rotating the parts as prescribed above for the different degrees of volatility. In this case, the user will get better results by closing the end with his or her finger.

In order to prevent unnecessary wasting of the volatile substances, the parts should be rotated until the indicator shows that all valves are closed when the device is not being used.

Due to the design, these articles are adapted for use with substances having any degree of volatility as well as being adapted to suit the individual's notion.

It is thought from the foregoing description that the advantages and novel features of the invention will be readily apparent.

It is to be understood that changes may be made in the construction and in the combination and arrangement of the several parts, provided that such changes fall within the scope of the appended claims.

What is claimed is:—

1. In a smoke device, a mouth piece including a bore, a smoke tube connected with the mouth piece, a tubular member forming a chamber and rotatably connected with the mouth piece, said tube passing through the chamber, the front end of the tube having a port therein and the front wall of the chamber having a recess therein for connecting the chamber with the tube through the port when the parts are in one position, the port being closed by a solid part of the tubular member when the parts are in another position, said tubular member having a port therein connecting the chamber with the atmosphere, and the inner end of the mouth piece having a recess therein which will connect the port with the chamber when the parts are in one position, the port being closed by a solid part of the mouth piece when the parts are in another position, and means for holding substances in said chamber.

2. In a smoke device, a mouth piece including a bore, a smoke tube connected with the mouth piece, a tubular member forming a chamber and rotatably connected with the mouth piece, said tube passing through the chamber, the front end of the tube having a port therein and the front wall of the chamber having a recess therein for connecting the chamber with the tube through the port when the parts are in one position, the port being closed by a solid part of the tubular member when the parts are in another position, said tubular member having a port therein connecting the chamber with the atmosphere, and the inner end of the mouth piece having a recess therein which will connect the port with the

- chamber when the parts are in one position, the port being closed by a solid part of the mouth piece when the parts are in another position, means for holding substances in said chamber, such means including a perforated cylinder, a perforated tube passing through the cylinder and encircling a part of the smoke tube, end pieces for the cylinder having perforations therein, and means for indicating when the ports are closed or open. 80
- 5 3. In a smoke device, a mouth piece including a bore, a smoke tube connected with the mouth piece, a tubular member forming a chamber and rotatably connected with the mouth piece, said tube passing through the chamber, the front end of the tube having a port therein and the front wall of the chamber having a recess therein for connecting the chamber with the tube through the port when the parts are in one position, the port being closed by a solid part of the tubular member when the parts are in another position, said tubular member having a port therein connecting the chamber with the atmosphere, and the inner end of the mouth piece having a recess therein which will connect the port with the chamber when the parts are in one position, the port being closed by a solid part of the mouth piece when the parts are in another position, means for holding substances in said chamber, 105

4. A mouthpiece including a passage, a chamber forming member and tobacco article holder connected to the mouthpiece and a medicating substance in said chamber, said member having a port therein connecting the chamber thereof with the atmosphere, said mouthpiece having valve means for controlling the port, and a tube extending through the medicating substance forming a continuous passage between the mouthpiece passage and the holder, said holder having a recess adapted to receive the tobacco article and communicating with the tube, said tube having a port, and valve means for the tube port connecting the chamber with the continuous passage, whereby when both valves are open air will pass through the medicating substance into the passage and medicate the smoke and when the valve for the tube port is closed, said chamber is placed out of communication with the passage and the smoke is not treated with medicated air. 100
